UNITED STATES PATENT OFFICE.

ORVILLE M. KNOX, OF KNOXBORO, NEW YORK.

RAIL-CLIP.

948,375.

Specification of Letters Patent. Patented Feb. 8, 1910.

Application filed March 19, 1909. Serial No. 484,373.

To all whom it may concern:

Be it known that I, ORVILLE M. KNOX, a citizen of the United States, residing at 5 Knoxboro, in the county of Oneida and State of New York, have invented certain new and useful Improvements in Rail-Clips, of which the following is a specification.

This invention relates to rail clips of the general type shown in my prior U. S. Letters Patent No. 764,362, granted July 5, 1904, 10 embodying a clip designed to firmly clamp the flange of the rail and to hold a nut-lock washer against retrograde rotation.

In the aforesaid patented construction, the 15 clip, which is in the form of an oblong rectangular block, is provided at one end with a clamping jaw to engage the flange of the rail, at its opposite end with a fulcrum shelf, and between said points with a washer-supporting surface through which opens a bolt-hole extending vertically through the block. Through this hole is passed the bolt which 20 fastens the clip to the tie, said bolt being provided at its upper end with a clamping nut. At one side of the washer supporting 25 surface the block is provided with a longitudinal rib or flange against which bears one of the side edges of the washer. The washer-supporting surface is arranged above 30 the plane of the fulcrum shelf, at the juncture of which portions a vertical shoulder is provided on opposite sides of which are arranged stops or projections. The said shoulder and stops are designed to prevent 35 inward and lateral movement of a suitable tool which may be rested and rocked upon the shelf to bend a wing or portion of the washer, initially projecting beyond the shoulder and above the shelf, into engagement 40 with the adjacent side of the nut to hold the latter against retrograde rotation. Such a construction of clip, having the flange and stop projections described, while effective in use, must be formed by casting 45 or forging, rendering it in the one case liable to fracture and in the other case expensive to manufacture.

The object of the present invention is to 50 provide a clip which, while possessing all of the advantages of the prior patented device, may be rolled and thus more easily and economically manufactured.

With these and other objects in view, 55 which will appear in the course of the subjoined description, the invention consists in

the features of construction and combination of parts hereinafter fully described and claimed, reference being had to the accompanying drawing, in which:

Figure 1 is a top plan view showing the 60 application of the invention to a tie and rail. Fig. 2 is a vertical longitudinal section of the same. Figs. 3 and 4 are perspective views of the clip. Fig. 5 is a plan view of the washer as it appears in its primal 65 form.

Referring now more particularly to the drawings, 1 designates the rail to be secured, 70 2 the tie or sleeper supporting the rail, and 3 my improved clip. The tie 2 may be a metallic tie of any preferred construction. The clip 3 consists of a body of, preferably, oblong rectangular form the base of which is curved or cut away at one end, as shown at 4, to lighten the structure and provide a reduced portion 5, which abuts against the inner edge of the base-flange 6 of the rail. This reduced portion forms an integral projecting clamping-jaw 7 to bear upon the inwardly-extending portion of the flange 6 and hold 80 the rail down upon the tie 2. The upper surface of the central portion of the clip 3 is flat or plane-surfaced to form a seat 8 for a purpose presently described, and extending through the body of the clip is an opening 9 which coincides with an opening 10 in the tie 2, said openings serving for the passage 85 of a securing-bolt 11, the head of which bears against the under side of the top of the tie 2, while the threaded shank thereof extends 90 a sufficient distance above the seat 8 of the clip to receive a nut 12, whereby the clip is fastened to the tie. At the end opposite the reduced portion 5 the clip is formed with an 95 outwardly and downwardly curved or beveled face 13, serving as a fulcrum ledge or shelf, and at the point where this ledge or shelf joins the body of the clip the body portion is provided with a vertical transverse shoulder 14 forming the boundary wall or 100 terminal of the seat 8.

The seat 8 is disposed above the plane of the shelf 13 and below the plane of the top surface of the reduced portion 5, at the juncture of which portions is formed a vertical 105 transverse flange or shoulder 15 arranged parallel with the aforesaid shoulder 14. The seat 8 serves as a support for a washer 17, consisting of an oblong rectangular plate of the primary form shown in Fig. 5, said plate 110

being provided with an eccentrically-disposed bolt-hole 18 for the passage of the bolt 11 and arranged between the seat 8 and nut 12 and clamped by the latter against said 5 seat. One of the end edges of the washer engages the shoulder 15, whereby the washer is held from rotation, and by reason of the eccentric disposition of the hole 18, which is located nearer said end of the 10 washer, the opposite end thereof is caused to provide a wing 19 of such length as to project beyond the shoulder 14 when the parts are primarily assembled as indicated by dotted lines in Fig. 5. This wing is adapted to 15 be bent up to engage one of the sides of the nut, as shown in Figs. 1 and 2, to hold the nut against retrograde rotation. It will thus be seen that as the washer itself is held from movement by the shoulder 15 and the 20 nut by the wing 19 all liability of the nut working loose and allowing the clip to shift or become detached is effectually avoided, and thus the rail will be securely clamped against movement.

25 In applying the parts to clamp the rail, the bolt 11 is passed up through the opening 10 in the tie and opening 9 in the clip after the latter has been placed in position, the washer laid upon the seat 8 with the bolt 30 projecting through the opening therein, and the nut then screwed home upon the bolt and, finally, the wing of the washer is bent up to engage the nut. This operation of bending up the wing is performed by inserting the end of a suitable tool into the space beneath the ledge or shelf 13 and projecting end of the washer, the shoulder 14 serving as a stop to properly gage the position of the tool, and then the tool is used to 35 pry or bend the wing upward to a substantially vertical position so as to engage one of the sides or corners of the nut. The ledge or shelf forms the fulcrum on which the tool may rock in describing its arc of movement, 40 and its beveled surface facilitates the application of the tool and allows the same to ride outward when operated to enable the wing to be easily bent into position.

The clip has a flat base 3^a which extends 45 continuously between the inner end of the reduced portion 4 and the outer end of the shelf 13 so as to rest squarely upon the tie and firmly support the clip from movement. This flat base and the firm support secured 50 thereby prevents rocking of the clip and strain upon the bolt from the pressure of the

tool on the shelf 13 in the operation of bending up the wing 19 of the washer 17.

It will be seen that a rail-fastening constructed in accordance with my invention, as shown and described, is simple, cheap, durable, and efficient and cannot possibly become accidentally disconnected from the rail unless torn bodily away with its fastening, while upon bending the wing back to its normal position it may be readily manually released to enable repairs to be made to the track structure or a new rail substituted for a damaged or worn-out one. It will also be seen that the structure of the clip with its described arrangement of shoulders and surfaces adapts it to be rolled instead of cast or forged, thereby enabling it to be more easily and economically manufactured.

Having thus fully described the invention, 75 what is claimed as new, is:—

The combination with a tie, and a rail resting thereon, of a rolled clip resting on the tie comprising a generally oblong rectangular body having a flat bottom and a 80 central flat top portion forming a washer-supporting seat, said body being formed with a bolt hole extending through said flat bottom and seat, the upper surface of the body being provided at one end with a shelf 85 arranged below the plane of and extending outwardly from one end of the seat and forming a transverse shoulder at its point of juncture therewith, and the opposite end of the body being cut away over the base and 90 extended above the plane of the seat, forming a rail-engaging jaw projecting beyond the opposite end of the seat and a transverse shoulder at the point of juncture of said jaw and seat, the said flat base extending continuously between the cut away portion below the jaw and the outer end of the shelf, a bolt projecting upwardly from the tie through the bolt hole in the clip, a nut 100 upon the upper end of the bolt, and a washer 105 clamped by the nut against the seat, said washer having an edge portion bearing against the latter-named shoulder and a wing bent from a normal position above the shelf into engagement with a side of the nut.

In testimony whereof I hereunto affix my signature in presence of two witnesses.

ORVILLE M. KNOX.
